UNITED STATES PATENT OFFICE.

WALTER SHAW, OF DEDHAM, MASSACHUSETTS, ASSIGNOR TO UNITED SHOE MACHINERY COMPANY, OF PATERSON, NEW JERSEY, A CORPORATION OF NEW JERSEY.

SHANK FOR USE IN THE MANUFACTURE OF BOOTS AND SHOES.

1,209,767.

Specification of Letters Patent. Patented Dec. 26, 1916.

Application filed May 21, 1915. Serial No. 29,546.

To all whom it may concern:

Be it known that I, WALTER SHAW, a citizen of the United States, residing at Dedham, in the county of Norfolk and State of Massachusetts, have invented certain Improvements in Shanks for Use in the Manufacture of Boots and Shoes, of which the following description, in connection with the accompanying drawings, is a specification, like reference characters on the drawings indicating like parts in the several figures.

This invention relates to boots and shoes and more particularly to shank stiffeners for use in the shanks of boots and shoes.

In the manufacture of the class of boots and shoes in which the outsole is molded in the shank to give a distinctive formation to the outsole and particularly to the tread portion thereof, it is important to provide a shank stiffener which will maintain the shape originally imparted to the outsole during the molding operation and also afford sufficient rigidity to support the arch of the foot. The shank stiffeners now in use, however, are comparatively expensive to manufacture and are unsatisfactory, especially when made of such material as leatherboard, since either they render the shoes stiff and unyielding or else they become broken and so impair the shape of the shoe.

An object of the present invention is to provide a shank stiffener which will be simple and inexpensive to manufacture and which will possess the essential characteristics necessary for a practical and satisfactory shank stiffener.

With this object in view an important feature of the invention is found in a shank stiffener comprising a body portion of yielding, elastic material shaped to conform to the longitudinal and transverse curvatures of the last and of the outsole and a stiffening element secured against displacement on the body portion of the shank stiffener and adapted to maintain its longitudinal curvature.

In the preferred embodiment of the invention the body portion of the shank stiffener consists of a rubber compound which, when vulcanized, will be soft and resilient. Preferably, and as herein shown, the forward end of the shank stiffener is formed and arranged to support the entire tread

portion of the sole in a horizontal plane and 55 owing to the particular characteristics of the material comprising the body portion of the shank stiffener it enables the molded shape of the sole to be maintained without destroying the flexibility of the shoe. 60

Other objects and important features of the invention will now be described in connection with the accompanying drawings and will then be pointed out in the claims.

In the drawings, Figure 1 is a perspective 65 view showing a shank stiffener of the present invention in position on a welted shoe and also showing the molded outsole to which the shank stiffener illustrated is shaped to conform; and Fig. 2 is a perspective view of the shank stiffener.

In the drawings showing a shank stiffener embodying a preferred form of the invention the body portion 2 of the stiffener comprises a yielding, elastic material which will 75 give the desired shape to the outsole and at the same time be strong and durable. A material particularly adapted for this purpose is rubber or rubber compounds, the ingredients of which are proportioned so as to 80 produce a soft, resilient body of rubber when vulcanized. This body portion of the shank stiffener is molded or shaped to lie within the overlasted edge 4 of the upper on the innersole 6 and extend from the heel seat 85 to the ball of the shoe. The upper surface of the body 2 is shaped to conform to the longitudinal and the transverse curvatures of the shank of the last and is preferably provided with a shallow recess 8 extending 90 longitudinally of the stiffener and terminating short of the forward end of the shank stiffener. The greater part of the length of the body 2 on its lower side is shaped to conform to the transverse curvature of the outsole in the shank and is of substantially uniform thickness. The forward end of the body is broadened to extend across the ball 95 of the shoe and its thickness is uniformly increased sufficient to compensate for the curvature of the bottom of the last from the tread plane thereof into the shank and provide a substantially flat surface 10 in the plane of the tread portion 12 of the last.

The particular formation of the forward 105 end of the stiffener is in accordance with the style of mold of the outsole 9.

As herein shown, the intersection of the

flat surface 10 and the longitudinally curved portion of the stiffener, as at 12, is received in the corresponding depression in the outsole thereby positioning the outsole on the 5 shoe and preventing it from being displaced during later operations on the shoe. In order to maintain the longitudinal curvature of the body 2 and enable the arch of the foot to be properly supported, a spring 10 plate 14 is located in the recess 8 in the under side of the body 2. This spring plate 14 is secured against displacement on the body by tacks 16 and extends beyond the rear end of the body so as to permit the 15 shank stiffener to be secured to the inner-sole.

It will be apparent that with the shank stiffener of the present invention, the shape and curvatures of the outsole in the shank 20 and at the ball portion thereof are entirely supported and, owing to the resiliency of the material comprising the body portion of the shank stiffener, the molded shape of the outsole is maintained without destroying 25 the flexibility of the shoe.

An important advantage of the shank stiffener above described is found in its strength and durability in use as distinguished from the relatively hard and stiff leatherboard 30 stiffeners which become broken and misshaped through the continued flexing and strain during wear.

It will be further noted that there are no metal parts to engage the outsole and wear 35 or cut through it as often occurs with sheet metal shank stiffeners which are shaped to the conformation of the outsole.

Having described my invention, I claim as new and desire to secure by Letters Patent of the United States:—

1. As an article of manufacture a shank stiffener for location between the insole and outsole of boots and shoes comprising a body portion of soft rubber shaped to conform to 45 the longitudinal and the transverse curvatures of the shank portion of the last and of the outsole, and a stiffening element secured against displacement on said body portion and adapted to maintain the longitudinal curvature of the shank.

2. As an article of manufacture a shank stiffener for location between the insole and outsole of boots and shoes comprising a body portion of yielding, elastic material shaped 55 to conform to the longitudinal and the transverse curvatures of the shank portion of the

last and of the outsole and having its forward end formed and arranged to support the tread portion of the outsole in a substantially horizontal plane, and a stiffening 60 element secured to said body portion and adapted to maintain the longitudinally arched portion of the stiffener.

3. As an article of manufacture a shank stiffener for location between the insole and outsole of boots and shoes comprising a body portion of comparatively soft rubber shaped to conform to the longitudinal and the transverse curvatures of the shank portion of the last and of the outsole and having its forward 70 end formed and arranged to provide a substantially level tread surface for the outsole, and a stiffening element secured to said body and adapted to reinforce the longitudinally arched portion of the shank 75 stiffener.

4. As an article of manufacture a shank stiffener for location between the insole and outsole of boots and shoes comprising a body portion of yielding, elastic material shaped 80 to conform, on its upper side, to the longitudinal and transverse curvatures of the shank portion of the last and, on its under side to the longitudinal and transverse curvatures of the outsole and having its forward 85 end formed and arranged to extend on to the tread portion of the last and support the tread portion of the outsole in a substantially horizontal plane relatively to the corresponding portion of the last, and a flat 90 spring member secured to the upper side of the body portion for maintaining the longitudinal curvature of the shank.

5. As an article of manufacture a shank stiffener for location between the insole and outsole of boots and shoes comprising a body portion of comparatively soft rubber shaped to conform to the longitudinal and the transverse curvatures of the shank portion of the last and of the outsole, the forward end of said body portion being formed 95 and arranged to provide a substantially flat surface for the support of the ball portion of the outsole in the plane of the tread portion of the outsole, and a flat spring stiffener 100 secured to said body portion for maintaining the longitudinal curvature of the shank 105 stiffener.

In testimony whereof I have signed my name to this specification.

WALTER SHAW.
